US00D462394S

(12) **United States Design Patent** (10) Patent No.: **US D462,394 S**
 Naghi et al. (45) Date of Patent: ** Sep. 3, 2002

(54) **LIGHT ATTACHMENT WITH
INTERCHANGEABLE HEADS FOR
PORTABLE ELECTRONIC AND
COMPUTING UNITS**

(75) Inventors: **David Naghi; Herschel Naghi**, both of Los Angeles; **Paul T. King**, Newbury Park, all of CA (US); **Anthony Martino**, Hamburg, NY (US)

(73) Assignee: **Technology Creations, Inc.**, Los Angeles, CA (US)

(**) Term: **14 Years**

(21) Appl. No.: **29/147,213**

(22) Filed: **Aug. 23, 2001**

(51) **LOC (7) Cl. 21-01**

(52) **U.S. Cl. D21/333; D26/62**
